PATENTED FEB. 11, 1908.

H. HERTZBERG & M. J. WOHL.
ELECTRICALLY HEATED SAD IRON.
APPLICATION FILED APR. 5, 1907.

UNITED STATES PATENT OFFICE.

HARRY HERTZBERG AND MAURICE J. WOHL, OF NEW YORK, N. Y.

ELECTRICALLY-HEATED SAD-IRON.

No. 879,046.

Specification of Letters Patent.

Patented Feb. 11, 1908.

Application filed April 5, 1907. Serial No. 366,529.

To all whom it may concern:

Be it known that we, HARRY HERTZBERG and MAURICE J. WOHL, citizens of the United States, residing at the city of New York, borough of Brooklyn, and State of New York, have invented certain new and useful 5 Electrically-Heated Sad-Irons, of which the following is a specification.

This invention is a sad iron for domestic, 10 laundry, tailoring and other purposes, wherein we contemplate employing means for electrically heating a mass of metal which constitutes the body of the iron.

One object of this invention is to secure 15 close contact between an electrically operated heater or resistance and a body or mass of metal, for the purpose of securing the rapid transmission of heat from said resistance to the mass of metal, whereby economy in the 20 consumption of the current and rapid heating of the iron for service are secured.

Another object is to overcome chafing of 25 the electrical conductors or wires at the point where they are attached or coupled to the device.

Another object is to overcome transmission 30 of the heat to the part of the iron which is to be grasped by the operator in handling or manipulating the device.

Broadly stated, our invention is a sad iron 35 composed of a body or mass of heat absorbing metal, one or more electrically operated heaters or rheostats inclosed by and within the body or mass, and means whereby said heater or rheostat, or the plurality of heaters or rheostats, are held in close contact with said body or mass.

The invention consists, further, of a yieldable 40 bushing connected to a part of the iron and receiving within itself the connected ends of a "cord" or cable by which the current is supplied to the wires leading to the heater or rheostat which is inclosed by the body or mass of metal.

In the accompanying drawings, we have 45 illustrated one practical embodiment of the invention, but the construction shown therein is to be understood as illustrative only, and not as defining the limits of the invention.

Figure 1 is a vertical longitudinal section, 50 partly in elevation, of a sad iron constructed in accordance with this invention, the plane of the section being indicated by dotted line 1-1 in Fig. 2 looking in the direction of the 55 arrow. Fig. 2 is a vertical cross section on

the line 2-2 of Fig. 1. Figs. 3 and 4 are, respectively, a vertical cross section on the line 3-3 of Fig. 4 and a horizontal section on the line 4-4 of Fig. 3, showing another embodiment of our invention wherein we employ a plurality of electrically operated heaters or rheostats within a mass of metal which constitutes the body of the sad iron. Fig. 5 is a horizontal section, partly in plan, of another embodiment of our invention wherein we employ a plurality of clamping wedges adapted to form spaces for ventilating the interior of the iron. Figs. 6 and 7 are detail views of different forms of yieldable bushings 60 adapted to anchor the supply cord or cable and the end portions of the wires for conveying an electrical current to a heater or heaters inclosed within the body of the sad iron. 65

A designates a sad iron which is composed of a body or mass of metal adapted to absorb and retain the heat which is developed by an electrical resistance, or a plurality of electrical resistances, when the current of electric energy is supplied to said resistance or resistances. The body or mass of metal may be 70 of any suitable or preferred shape or dimension, and as shown, said body is provided with an imperforate flat bottom member, a. The body, A, may be composed of iron, copper or other metal, and the entire body may be cast in a single piece, as shown by the drawings; or the body may be composite, that is to say the upper part thereof may consist of iron and the lower member, a, of copper, in which case the mass of metal consists of two or more pieces adapted to be 75 united in a suitable way. It is to be understood, therefore, that we may employ a body composed of one metal, all the parts of which are integral, or we may employ a composite metallic body, the parts of which are made 80 separately and united in a substantial manner to produce an integral body. 90

The body, A, of the sad iron shown in Figs. 1 and 2 is provided with a longitudinal chamber, a', in which is arranged a single electrically operated heater or rheostat, and means for clamping said heater or rheostat into close mechanical engagement with the imperforate bottom member, a, of the said body or mass. 100

We may employ any suitable or well known electrically operated heater within the chamber, a', of the body or mass, A, but we prefer a heater wherein a thin metallic wire or ribbon, b, is coiled or wound on a core, b', com- 110

posed of a thin layer of insulating material, such as mica, said core and the resistance formed by the metallic wire or ribbon being inclosed by and between layers of insulating material, preferably mica, indicated at b^2 , b^3 . The electrical heater, indicated in its entirety by the reference character B, is arranged within the chamber, a' , so as to have its layer, b^2 in direct contact with the imperforate bottom member, a , of the body, A, the electrical resistance wire, b , being next to the layer, b^2 , so that it is practically in mechanical contact with said member, a , although insulated electrically therefrom by 15 the thin mica layer, b^2 .

In the construction shown by said Figs. 1 and 2 we contemplate the employment of a lining, C, which is a poor conductor of heat, said lining being composed of asbestos or 20 other non-conductor. The lining may be of any suitable thickness, and it is placed against the under surface of the top member or part of the body or mass of metal.

For securing the close mechanical contact 25 between the electrically operated heater and the bottom member, a , of the body, A, we employ a wedge or wedges adapted to clamp one part upon the other. As shown, coöperating wedges, D, E, are arranged within the 30 chamber, a' , between the aforesaid heater and the non-conductor lining, C. Each wedge, D or E, is provided with an inclined face on one side and a flat face on the other side in order that the two wedges may be 35 assembled reversely to each other, and with their inclined faces in engagement one with the other, while the flat face of the wedges engage with the heater and the lining, respectively. In assembling the parts comprising 40 the device, the electrical heater is placed within the chamber, a' , and rests upon the imperforate bottom member, a ; the wedge, D, is then inserted with its large end foremost and it rests upon the insulating 45 layer, b^3 , of said heater, and thereafter the wedge, E, is forced into position, whereby said wedge, E, engages with the wedge, D, and with the lining, C. The operation of forcing home or driving the wedge, E, into place 50 causes the wedge, D, to press the electrical heater into close contact with the bottom member, a , and thus the electrical resistance is clamped firmly and solidly against the bottom member, whereby the heat developed in 55 said resistance by the passage of electric current will be transmitted rapidly to, and absorbed by, the bottom member, a , of the body or mass of metal. The wedges, D, E, are inserted in the body, A, for the edges at the 60 ends and sides of the said wedges to engage with the body or mass, A, and said wedges are, also, in mechanical contact with one another, whereby the heat absorbed by the wedge, D, from the electrical heater will be 65 communicated or transmitted by the said

wedges to the body or mass. The lining, C, however, minimizes the transmission of the heat to the upper part of the body or mass, so that the heat is applied to, or concentrated on, the bottom member, a .

The iron, A, is provided with any suitable form of handle, G, for manipulating said iron. As shown, said handle is composed of a material which is a poor conductor of heat, and the handle is fastened to short posts, g 70 75 which are either integral with a body, A, or are attached rigidly thereto.

The body, A, is formed with a solid end adapted to close one end portion of the chamber, a' , while said chamber opens 80 through the other end of said body. This end of the body is adapted to be closed by a member, H, preferably in the form of a plate adapted to be fastened to the body, A, and the bottom member, a , thereof. This end member, H, is provided with an up-standing arm, h , which terminates in an eye or loop, h' . In this eye or loop is arranged a bushing adapted to form an anchorage for a cord or cable, I, the latter serving to convey an 90 electrical current to the wire, j , by which said current is conveyed to the resistance, b , of the electrical heater. As is known in the art, the cable or cord, I, is composed of wires 95 twisted together and provided with means, such as a plug, for attachment to a socket of an electric circuit. The conductors, j , are attached to the resistance, b , of the electric heater, and these conductors are led through suitable openings or channels which are provided in the member, H, the ends of said conductors, j , being joined to the conductors of the cord or cable, I, in a manner well understood by those skilled in the art. The loop or eye, h' , is integral with the upper 100 105 extremity of the member, H, said loop or eye serving as a support for a bushing which is composed preferably of wire which is coiled into the form shown in Fig. 6 or in Fig. 7 so as to produce a bushing, K, or K'. The 110 bushing, K' of Fig. 7 is tapering longitudinally whereas the bushing, K, shown in Fig. 6 is composed of coils, k , which are larger in diameter than the coils, k' , thus producing a bushing which is shouldered at a point intermediate of its length. The bushing, K, or K', is fitted in the eye or loop, h' , for the end portions of said bushing to project beyond the eye or loop. When the bushing, K, of Fig. 6 is used in the manner shown in Fig. 1, 115 120 the shoulder of said bushing engages with one end portion of the eye so as to limit the bushing against movement within said eye. The cord or conductor, I, passes into the bushing at its small end, and said cord is 125 provided within the large end of the bushing with a knot, i , the latter preventing endwise movement of the cord or cable in said bushing and overcoming any tendency of the conductors, j , and the cord or cable to pull apart 130

in the use of the iron. The primary function, however, of this yieldable bushing is to overcome the tendency of the cord or cable to chafe or rub the insulation from the wires thereof.

In Figs. 3 and 4 of the drawings we have shown a sad iron provided with two or more pairs of electrical heaters for the purpose of quickly heating a large heavy sad iron, such as those used in laundering and tailoring operations. The body or mass, A, is provided with a plurality of longitudinal chambers, m, which are separated by intermediate walls, m', of metal, the latter being integral with the body or mass, A'. Each chamber, m, contains two of the electrical heaters indicated at B', which heaters are arranged lengthwise of the chamber and are arranged for engagement with the opposite side walls of said chamber. Said heaters are forced into close mechanical contact with the respective side walls of the chamber by coöperating metallic wedges, D', E', the latter having engagement with the respective heaters and with the body or mass of metal, whereby the heaters are adapted to heat the iron and the walls, m', thereof, and said wedges communicate the heat absorbed thereby to the body or mass of metal, thus quickly transmitting the heat to the body or mass of metal for the purpose of uniformly and rapidly bringing the iron to a temperature required for service. The electrical heaters in the several chambers may be connected in series or in multiple, and the several chambers, m, are adapted to be closed individually, or by a plate, m², which is common to all of said chambers.

Fig. 5 of the drawings represents another embodiment of our invention wherein we employ a perforated layer of mica, b⁵, as the core for the winding of the electrical resistance wire or ribbon, and a plurality of short wedges adapted to be used in lieu of the wedge, E, said short wedges coöperating with a single wedge, D, and providing certain spaces within the body or mass of metal for the escape of hot air therefrom, thus ventilating the body or mass of metal above the imperforate bottom member, a, thereof.

It will be understood that the perforated core b⁵, of mica is used in lieu of an imperforate core, b', shown in Figs. 1 and 2, and further, that the resistance wire or ribbon is coiled or wrapped on this core, the parts being inclosed by and between other layers of mica, such as the layer, b², b³. If desired, however, all the layers of mica may be perforated for ventilating purposes. The electrical heater, B², of Fig. 5 is constructed in substantially the manner heretofore described in connection with Figs. 1 and 2, except that one or more of the layers of mica are perforated. Such a heater is placed within the chamber of the body or metallic mass,

A², and against this heater is placed a wedge, such as D. Instead of employing a single wedge, E, as in Figs. 1 and 2, we employ a plurality of short wedges, E', which are not as wide as the wedge, D, and are considerably shorter. These wedges, E, are adapted to be inserted in the manner heretofore described so as to space the wedges, E', and provide certain openings, e, for the escape of heat from the chamber of the body or mass of metal.

Having thus fully described the invention, what we claim as new, and desire to secure by Letters Patent is:

1. In a device of the class described, a chambered metallic body having a bottom member, an electrically operated heater in said body, and coöperating wedges for confining said heater in close contact with said bottom member.

2. In a device of the class described, a chambered metallic body having a bottom member, a plurality of electrically operated heating elements in said body, and means within the body for clamping said heating elements into close contact with said bottom member.

3. In a device of the class described, a chambered metallic body having a bottom member, a plurality of electrically operated heating elements in said body, and wedges for clamping said heating elements into close contact with said bottom member.

4. In a device of the class described, a chambered body or mass of metal, an electrical heater therein, and a plurality of coöperating wedges for clamping said heater into close contact with said body, certain of the wedges being spaced to provide for the circulation of air between them.

5. In a device of the class described, a chambered body or mass of metal, an electrical heater therein, and upper and lower wedges for clamping said heater into close contact with said body or mass of metal, certain of said wedges being spaced and providing air circulation spaces through the chamber of said body or mass.

6. In a device of the class described, a chambered body or mass of metal, an electrical heater therein, and a plurality of spaced wedges engaging with said heater and forming in the body spaces for the circulation of air.

7. In a device of the class described, a body composed of heat-absorbing metal and provided with a plurality of chambers, a heater in each chamber, and wedging means in each chamber for clamping the heater in the same chamber into close contact with the body.

8. In a device of the class described, a body composed of heat absorbing metal and provided with a plurality of chambers, a plurality of heaters in each chamber, and co-

operating wedges between said heaters and adapted to confine the latter into close contact with the metal of the body.

9. In a device of the class described, a body provided with a plurality of chambers which are separated by intervening walls, an electrical heater in each chamber, and wedges for clamping each heater into close contact with a wall of said body.

In testimony whereof we have signed our 10 names to this specification in the presence of two subscribing witnesses.

HARRY HERTZBERG.
MAURICE J. WOHL.
